UNITED STATES PATENT OFFICE

RALPH E. THOMPSON, OF BROOKLINE, MASSACHUSETTS, ASSIGNOR TO GILLETTE SAFETY RAZOR COMPANY, OF BOSTON, MASSACHUSETTS, A CORPORATION OF DELAWARE

SAFETY RAZOR AND BLADE

Application filed November 20, 1930. Serial No. 496,934.

This invention relates to safety razors and safety razor blades and has for its primary object the provision of a simplified razor and blade construction.

5 In one aspect my invention more particularly relates to safety razors of the type wherein a blade is supported and clamped between cap and guard members by means of some form of screw thread connection or the like. The blade is thus clamped for shaving and in order to thoroughly rinse the razor and blade following the completion of a shaving operation and prior to laying them away, the clamping means must be released 10 to a position substantially freeing the blade from clamping action, and the rinsing and drying operations are greatly facilitated if the blade is well separated from the cap and guard. In accordance with one embodiment 15 of my invention I provide the blade with a plurality of resilient tabs normally extending outwardly from the opposite faces thereof in a manner to form resilient cushions on opposite sides of the blade acting to thus automatically cushion and space the blade from the cap and guard when released. The provision of such a blade comprises a further object of my invention.

20 Razors of the type above referred to as heretofore commonly constructed embody some form of locating stud or studs on the cap or guard members, which studs are adapted to pass through apertures in the blade and other member and thereby locate 25 all three members to proper shaving alignment. According to another aspect of my invention, I provide resilient tabs on the blade which normally extend outwardly from the opposite faces thereof and I provide 30 corresponding grooves or sockets within the blade engaging faces of the cap and guard for receiving these tabs. These tabs, in conjunction with the centrally disposed locating 35 hole in the blade, serve to locate the blade between the cap and guard and thereby eliminate the necessity of the above-mentioned 40 blade locating studs which have heretofore been provided on the cap or guard, and the tabs furthermore also serve the cap and 45 guard spacing function above defined. The

55 tabs will preferably be so symmetrically formed on the blade as to fit with the blade in any position in the razor. The provision of a safety razor and blade thus constructed comprises another object of my invention.

In the accompanying drawings I have illustrated certain specific embodiments of my invention but it will be understood that the invention can be otherwise embodied, it is merely essential that the structural features 60 and relations shall be such as to maintain the cap, guard and blade in yieldable or cushioned and spaced relation for cleansing and drying purposes. In the embodiment including the aligning features it is merely essential 65 that the aligning means on the blade be yieldable and form resilient cushions to maintain the parts in spaced relation for cleansing and drying purposes. The drawings are not to be construed as defining or limiting the scope 70 of the invention, the claims appended hereto being relied upon for that purpose.

Referring to the figures of the drawings, Fig. 1 is a perspective view of a blade constructed in accordance with my invention;

75 Fig. 2 is an elevation of a modified form of blade;

Fig. 3 is a longitudinal sectional view 80 through a razor having the blade of Fig. 1 therein;

Fig. 4 is a transverse sectional view taken on line 4-4 of Fig. 3;

Fig. 5 is an exploded view of another form 85 of my improved blade and razor; and

Fig. 6 is a longitudinal sectional view 90 through the razor and blade of Fig. 5 assembled.

In Fig. 1 of the drawings I have illustrated my invention as applied to a blade of the new Gillette type. This blade 10 comprises two 95 oppositely disposed cutting edges 12, and a centrally disposed locating slot 14 there-through, and is adapted to be used in a razor or holder having cap and guard members with cooperating blade engaging faces which 100 curve the blade to a transverse position, the blade being transversely flexible for this purpose. When the razor is released from its clamped position, the straightening of the blade to its normal plane shape somewhat

separates the cap and guard but in order to more fully separate these members from the blade I form resilient tabs 16 and 18 thereon. As illustrated in Fig. 1, these tabs are struck 5 out from the body of the blade and two of the tabs 16 project outwardly beyond one face of the blade and the other two tabs 18 project outwardly beyond the other face thereof. Two of these tabs are also located 10 on each side of the transverse center line of the blade and two are also located on each side of the longitudinal center line of the blade. When the tongues or tabs are stuck out of the body of the blade, as in the case 15 herein shown, the recess formed beneath each tongue will receive the latter, thereby housing or partly housing the same when the blade is fully clamped in shaving position between the cap and guard.

20 In Figs. 3 and 4 I have illustrated this blade 10 in partially released position between cap and guard members 20 and 22 of a safety razor. It will be noted that the straightening of the blade to or toward its 25 plane position somewhat separates the cap and guard and that the tabs 16 and 18 act to further separate these members from the blade. I desire to particularly call attention to the fact that this separating action 30 is facilitated by the locating of the tabs in positions between the longitudinal center line of the blade and its cutting edges, as particularly shown in Fig. 4.

35 While I prefer to form the tabs as an integral part of the blade, it is obvious that the same may be otherwise formed and secured to the blade. For example, in Fig. 2 I have illustrated a blade 30 similar to the blade 10 but having two resilient tabs 32 secured 40 to opposite sides thereof by spot welding at the ends 34. The two tabs are located on opposite sides of the blade and the free ends thereof extend outwardly from the blade faces in a manner like the tabs of the blade 45 10. It will also be noted that the free ends of these two tabs are located on opposite sides of the longitudinal center line of the blade and the free ends thereof are substantially coincident with the transverse center line of 50 the blade. Such locating of the two tabs permits them to function midway of the blade to most efficiently perform the blade separating operation.

55 A further modified form of the blade is illustrated in Figs. 5 and 6. This blade 40 has a centrally disposed locating hole 42 therethrough and two tabs 44 are respectively formed on the center line of the blade and 60 respectively at opposite sides of the hole 42 therethrough. These tabs are preferably blanked out of the blade body with the tabs respectively extending outwardly at opposite faces of the blade. The tabs are also preferably so located that their free ends extend in

directions away from the center hole 42. The tabs 44 serve the blade separating function above described in reference to the blades 10 and 30 and also serve a blade locating function now to be described.

70 This blade 40 is particularly adapted to be used in a razor or holder of the type shown in Figs. 5 and 6. This razor comprises a cap 50, a guard 52, and a clamping handle 54, the handle being adapted to thread onto a stud 50 extending outwardly from the cap. The blade engaging faces of the cap and guard are shallow recessed at 58 and 60, these recesses being of a width corresponding 75 to the free ends of the blade tabs 44. When the blade is placed on the cap with the stud 56 engaged through the hole 42, and only these tabs 44 extending into the groove 58, the blade is thereby accurately located relatively to the cap. The guard is likewise located by the stud engaging through the hole 62 therein and the other blade tab engaging in the groove 60. The parts are thereby accurately located, the tabs 44 serving the double function of locating the cap and guard relative 80 to the blade and separating the cap and guard from the blade when the handle 54 is released. It will be clear that this construction considerably simplifies this type of razor since the easily formed recesses 58 and 60 serve the blade-locating purpose heretofore requiring relatively expensive locating studs to be 85 formed on the cap or guard.

90 I have described the tabs as formed integrally or spot welded to the blade and herein use as a generic expression covering both forms the term metallurgically united.

95 It is to be observed that the tabs, formed 100 preferably by slotted portions of the blade, in every instance serve as yieldable cushions located in engagement with the cap and guard and are adapted to maintain the parts in 105 amply spaced relation for cleansing and drying. The cushioning effect prevents rattling 110 of the parts even though the spacing is at its maximum for successful cleansing and drying. In this connection attention is also 115 called to the fact that the cushioning means occupy small areas only in spaced relation from the exterior outline of the blade, which is a most desirable feature when utilized in the cleansing and drying operations of safety razors.

120 It is further to be observed that the resilient spacing and cushioning means are housed in various ways in the razor or razor head, thereby permitting direct engagement of the blade by the clamping members directly to grip the blade to clamp it in shaving position. In Figs. 1, 3, 4, 5 and 6 the resilient cushioning and spacing means are housed partly in 125 the blade and partly by the clamping members when the blade is in clamped position for shaving. In Fig. 2 the housing of the spacing cushions is accomplished solely by 130

the clamping members by using a curve of shorter radius on the inner surface of the cap member than on the co-operating surface of the guard member. In this manner the resilient spacing cushioning means are adequately housed while the blade is gripped directly by the clamping members to hold the blade in shaving position.

The blade herein shown has an adjustable position for shaving and a spaced position for cleansing and drying.

Having thus described my invention, what I claim as new and desire to secure by Letters Patent is:—

15 1. A safety razor blade having flat resilient tabs struck out from the body of the blade, normally extending outwardly from the opposite faces thereof, and movable into the plane of the blade said tabs extending in planes defining a small acute angle with the plane defined by the blade.

20 2. A safety razor blade having resilient tabs struck out from the body of the blade, normally extending outwardly from the opposite faces thereof and capable of being sprung back into the plane of the blade and at opposite sides of the transverse center line therethrough said tabs extending in planes defining a small acute angle with the plane 25 defined by the blade.

30 3. A safety razor blade having resilient tabs struck out from the body of the blade, normally extending outwardly from the opposite faces thereof and capable of being sprung back into the plane of the blade and at opposite sides of the longitudinal center line therethrough said tabs extending in planes defining a small acute angle with the plane defined by the blade.

40 4. A safety razor comprising a cap and a cooperating guard, a blade therebetween, resilient tabs carried by the blade and normally extending outwardly from the opposite faces thereof and extending in planes at a small

45 acute angle to the blade, the blade engaging faces of the cap and guard being grooved to receive the tabs and thereby align the cap, guard and blade, and means for clamping the cap and guard on the blade.

50 5. A safety razor comprising a cap and a cooperating guard, a stud extending from the blade engaging face of the cap, a blade between the cap and guard, the guard and blade having locating holes therethrough for

55 receiving the stud, resilient tabs struck out from the blade and normally extending outwardly from the opposite faces thereof, the blade engaging faces of the cap and guard being grooved to locate the blade by receiving the tabs thereinto, and means for clamping the cap and guard in blade holding position.

60 6. A safety razor comprising a cap and a cooperating guard, a stud extending from the blade engaging face of the cap, a blade between the cap and guard, the guard and blade

having locating holes therethrough for receiving the stud, two resilient tabs struck out from the body of the blade along the longitudinal center line therethrough and at opposite sides of the said hole therein, the tabs being connected to the blade at the ends adjacent to the hole and having their outer ends respectively extending outwardly from the opposite faces of the blade, the blade engaging faces of the cap and guard being grooved to locate the blade by receiving the tabs thereinto, and means for clamping the cap and guard in blade holding position.

70 7. A safety razor blade adapted to be clamped between cap and guard members, each member having recesses in its body located in opposed clamping portions thereof and spring tongues extending flatwise out of the plane of the blade on opposite sides thereof and in registration with said recesses.

75 8. A safety razor comprising cooperating cap and guard members adapted to clamp a flexible blade between them, and a blade having resilient tongues extending normally out of the blade on opposite sides in flatwise relation thereto, and being adapted to engage the cap and guard members and space the blade from both members when the latter are separated, whereby the cap, blade and guard may be resiliently retained in spaced 80 relation for rinsing or cleansing.

90 9. A safety razor head including a cap, guard and an interposed blade, said blade being slotted to form in said blade resilient tongues comprising cushioning means, means on said cap and guard in engagement with said tongues to maintain said blade in spaced relation from the cap and guard whereby the cleansing and drying operations of said razor head may be facilitated, and means to draw 95 said cap and guard together against the resilience of said tongues to grip and hold said blade in shaving position.

100 10. A yieldably and resiliently cushioned razor blade having aligning means and a plurality of portions forming raised resilient depressible cushions located on opposite sides of the blade and the aligning means thereof, said portions being also located in relatively 105 widely spaced relation both longitudinally and transversely with respect to each other, whereby the blade may be yieldably and resiliently clamped in a razor blade holder either in spaced or shaving position.

110 11. A yieldably and resiliently cushioned 110 razor blade having cushioning means comprising yieldable resilient raised depressible portions having free ends located in spaced relation from the exterior outline of the blade and in longitudinally spaced relation to each other on opposite sides of the blade whereby the blade may be yieldably and resiliently positioned in a razor blade holder in spaced 115 cleansing position or gripped in clamped position for shaving.

12. A yieldably and resiliently cushioned razor blade having aligning means and a plurality of tabs located on opposite sides of the blade and its aligning means, said tabs forming raised resilient yieldable depressible cushions located in spaced relation from the exterior outline of the blade and in widely spaced relation from each other both longitudinally and transversely. 70
13. A razor blade having raised depressible resilient cushioning means of limited extent on opposite sides of the blade and located in longitudinally spaced relation to each other and to the exterior outline of the blade, whereby the blade may be supported in spaced relation for cleansing or gripped in clamped position for shaving substantially as described. 75
14. A safety razor blade having slotted longitudinal portions having free ends located in spaced relation longitudinally inside of the exterior outline of the blade, said portions being on opposite sides of the blade, said portions being resilient and extending to raised positions at their free ends at an acute angle to the plane of the blade, said free end portions being readily and freely depressible. 80
15. A safety razor blade having cushioning means secured thereto and located on opposite sides of the blade in spaced relation to each other and to the exterior outline of the blade, said cushioning means comprising resilient members of limited area having raised readily depressible free ends, whereby the blade may be supported in either spaced cleansing relation or gripped in clamped position in a holder for shaving substantially as described. 85
16. A safety razor head including cap and guard members and an interposed blade, said head having aligning means, a plurality of resilient depressible cushioning and spacing means composed of hard material of substantially uniform thickness, located between the cap and blade and also between the guard and blade, said means occupying small areas only in spaced relation from the aligning means and spaced relation from the exterior outline of said razor head, whereby the cap, blade and guard may be supported in spaced relation for cleansing and drying purposes, means in said razor head for housing said cushioning means when in depressed condition, means to draw the razor head parts together and means to engage the blade directly and in spaced relation from the spacing means whereby the blade may be gripped and maintained in shaving position substantially as described. 90
17. A safety razor head having a transversely curved cap member and a coacting guard member and an interposed flexible blade having shaving edges, means to draw said members together, means on said mem- 95
- bers to engage the blade directly on opposite sides thereof to maintain the blade in shaving position, resilient depressible cushions located and supported between the cap and blade and also between the guard and blade whereby the blade may be supported by said cushions in spaced cleansing and drying relation with reference to said members, said cushions being readily depressible and located in longitudinally spaced relation to each other and means in said razor head to house said cushions in a position remote from the shaving edges of the razor blade. 100
